[57] CLAIM

The ornamental design for a van top, as shown and
described.

DESCRIPTION

FIG. 1. is a top right front perspective view of a van top
showing my new design;

FIG. 2 is a left side elevational view thereof;

FIG. 3 is a top plan view thereof;

FIG. 4 is a bottom plan view thereof;

FIG. 5 is a front elevational view thereof;

FIG. 6 is a rear elevational view thereof; and

FIG. 7 is a top, right, front perspective view of a van
top showing a second embodiment of my new design
the sole difference being in the omission of the win-
dows.
